PILL DISPENSING UNIT

Richard Horland, West Orange, N.J.

Application April 15, 1958, Serial No. 728,571

2 Claims. (Cl. 206—42)

This invention relates to dispensing devices for pills, tablets, and the like.

One often has difficulty in extracting one or more tablets from a container, and this represents a considerable inconvenience, particularly when one is required to take medication in the form of tablets at relatively frequent intervals. Often, in emptying a container into the palm of the hand, one dispenses far more than the desired number of tablets, and as a result, has difficulty returning the unused tablets to the container. Or, one may actually cause a number of the tablets to drop and become lost or unusable.

In view of the above, the main object of the present invention is to provide a device for dispensing tablets or pills, which device will be designed particularly for facilitating the extraction of the tablets individually, without possibility of the remaining tablets of the dispenser becoming accidentally dispensed.

Another object is to provide a tablet dispenser of the kind described which will be capable of manufacture at a comparatively low cost, considering the benefits to be obtained from the use thereof. The invention is so designed that the dispenser might be a single-use, disposable container in which the medications are sold. Alternatively, the device with some refinements might be a container to be retained permanently by the user, with said container being refilled with tablets whenever it becomes fully exhausted of its contents.

Another object is to provide a tablet dispenser of the character described which will be compactly formed, to permit a large number of tablets to be held therein, considering the relatively small, flat shape of the device.

Still another object is to so form the device that one can readily determine the number of unused tablets remaining therein.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a tablet or pill dispenser according to the present invention, with the lid raised, with tablets shown therein.

Fig. 2 is a slightly enlarged, fragmentary perspective view showing the dispensing opening of the device, with a tablet in the process of being removed.

Fig. 3 is a transverse sectional view, on an enlarged scale, taken substantially on line 3—3 of Fig. 1.

Fig. 4 is a still further enlarged, detail sectional view of one of the lid hinges, substantially on line 4—4 of Fig. 1.

Fig. 5 is a transverse sectional view on the same cutting plane as Fig. 3, with the lid closed.

Fig. 6 is a plan view of a modified form, the container

2

being shown in full and dotted lines in retracted and dispensing positions respectively, a portion of a housing for the container being broken away, tablets being shown in the container.

5 Fig. 7 is a perspective view, a portion being broken away, of the form of the invention shown in Fig. 6, with the container partially removed from the housing to permit dispensing of one of the tablets.

Fig. 8 is a plan sectional view substantially on line 10 8—8 of Fig. 7.

Fig. 9 is a view substantially like Fig. 8 showing another modified construction, parts being shown broken away, the tablets being omitted.

Fig. 10 is a view like Fig. 8 showing still another modification, parts being broken away, tablets being shown in the container.

Fig. 11 is a front elevational view, partly in section, of a container embodying still another modified form of the invention, with the closure member in closed position, parts being broken away.

Fig. 12 is a front elevational view of the bottom end of Fig. 11 showing the closure member in open position.

Fig. 13 is a bottom perspective view of the closure member.

25 Fig. 14 is a view similar to Fig. 11 showing yet another modification of the invention.

Fig. 15 is a vertical sectional view taken on the plane of the line 15—15 of Fig. 14.

Fig. 16 is a horizontal sectional view taken on the plane 30 of the line 16—16 of Fig. 14.

Referring to the drawings in detail, in the form of the invention shown in Figs. 1—5, the pill or tablet dispenser has been generally designated at 10, and includes a container provided with flat, closely spaced bottom and top walls 12, 14, respectively, separated by and secured to side walls 16 and end wall 18. The container, which has been generally designated at 19, may be formed entirely of a springable transparent plastic, so that one can at all times see the extent to which the container contains, comprising a plurality of tablets T, have been depleted.

45 In any event, it will be seen that the container has a generally flat shape, so that all the tablets are disposed in a single layer, in a common plane. At one end, the container may be squarely formed by the end wall 18 which extends perpendicularly to the respective sides, while at the other end 21, the container may be beveled, for the purpose of providing a path along which the tablets move, which path will be particularly designed to facilitate the 50 tablets being shifted into a dispensing position.

At one corner, the top and bottom walls are formed with angularly shaped dispensing recesses or openings 20, 22, which are in registration with each other, and which are so associated as to permit a portion of the next tablet 55 that is to be dispensed to be visible through the openings and to be capable of being grasped between one's thumb and index finger. The openings are smaller in diameter than the diameter of the tablets. Walls 16, 18, at this corner of the container, are free of connections to the bottom and top walls, and are of a springable nature, providing spring tongues 24, 26 which are tensioned to normally extend in abutting relationship as in Fig. 1, to close the corner and prevent the tablets from moving out of the container.

60 However, if one desires a tablet, he need merely grasp the tablet, a portion of which is exposed through the openings 20, 22, that is, that tablet which is nearest the spring tongues 24, 26. One then pulls outwardly on the tablet, causing the same to spread the tongues 24, 26 to the Fig. 2 position, enlarging the opening, so that the 65 tablet is eventually pulled out laterally of the container.

The spring tongues immediately return to their normal position, by reason of the inherent spring tension thereof.

Designated at 28 is a longitudinally and centrally extending partition secured to and extending between the top and bottom walls. Partition 28 at one end abuts the wall 18, while at the other end the partition terminates well short of the obliquely disposed end wall. The partition and beveled end wall 21 define a tortuous path along which the tablets move toward dispensing position.

Designated at 29 is a lid, which is swingably mounted upon hinge leaves 30. The leaves 30 are, in actuality, of hook shape in cross section, said leaves being loosely positioned through slot-like openings 31 (see Fig. 4) of the lid. The lid thus swings between the open and closed positions shown in Figs. 1 and 5, respectively. Of course, the dispenser could be made without the lid 29.

Means is provided for retaining the lid in its normal, closed position. To this end, there is provided an integral latching tongue 34, having a transverse corrugation engageable in a latching recess 36 formed in the front side wall 16 of the container. The tongue is of springable formation, so as to permit the same to readily spring into and out of the latch recess.

In Figs. 6-8, there is shown a modified construction generally designated 38, including a container 40 and a housing 42, the housing serving the function of a lid in that it closes the dispensing opening 44 provided in one corner of the container.

The container 40 is of rectangular configuration, and has flat top and bottom walls closely spaced apart as shown in Fig. 7, said top and bottom walls having angular recesses, providing a dispensing opening 44, just as in the first form of the invention. The diameter of the dispensing opening is smaller than the diameter of the tablets. The side walls of the container 40 are secured to the top and bottom walls, and one side wall and one end wall terminate in spring tongues 46, 48 normally abutting as in Fig. 7. The spring tongues are adapted to be resiliently spread, in a manner as in Fig. 2, whenever the container is partially extended from its associated, open-ended housing 42 to an extent sufficient to expose the dispensing opening. The partitioning of container 40 could be that of Fig. 1. However, by way of varying the arrangement, one can have a container provided with two longitudinal partitions 50, 52, one extending from one end wall and the other extending from the other end wall, to provide a serpentine or tortuous path, for the tablets.

Referring to Fig. 9, there is here shown a modified construction generally designated 54, which is identical in all respects to the form shown in Fig. 6, with the exception that the dispensing container 56 has dispensing openings at both ends, in diagonally opposite corners. Thus, at one end there is a dispensing opening 58 normally closed by spring tongues 62, 64, while in the other end there is a dispensing opening 60, normally closed by spring tongues 66, 68. The container can be extended out of either end of the open-ended housing, to permit tablets to be withdrawn from both ends, thereby eliminating to a considerable extent the necessity of shifting the tablets to dispensing position.

In Fig. 10 there is shown another modification wherein the device is generally designated 70 and includes an open-ended housing 72 similar to that of Figs. 8 and 9. Designated at 74 is a dispensing container containing a large number of tablets. This is a large size of the dispenser, but in principle the construction is unchanged from that of Fig. 9. Thus, there are a plurality of partitions 76 extending from the opposite walls of the device, forming a tortuous path, with opposite ends of said path terminating at dispensing openings 78, 80 located in diagonally opposite corners and normally closed by spring tongues 82 and 84 and spring tongues 86, 88 respectively. The diameters of the openings 78, 80 are smaller than the diameter of the tablets.

Referring now to Figs. 11-13, the dispenser 90 shown herein is in the form of a rectangular-shaped transparent springable plastic shallow box-like container 91. The interior of the container is divided by a partition wall 92 to form a circuitous path for movement of the tablets T. At one corner the top and bottom walls are cut away providing a dispensing opening 95. The side and end walls 96 at said corner meet but are not fastened together thereby forming flexible tongues 97 and 98. The dimensions of the tablets are larger than the dimensions of the opening 95 so that normally the tablets will not fall through the opening.

In accordance with the invention, a hinged closure member 100 is provided for yieldably closing the opening 95. This closure member comprises a strip 101 of flexible plastic or other suitable material and secured to one end of the strip is a cap 102 formed of thin resilient sheet metal. Cap 102 has a box-like body with three sides 103 and a top 104, conforming to the shape of the opened corner of the container, the sides being readily spreadable. The strip 101 is readily fastened to the end of the container adjacent the opening 95 by adhesive or in any other suitable manner so as to serve as a hinge support for the cap 102. When the strip is so secured, the cap 102 can readily be slipped over the corner of the container closing the opening 95. When it is desired to extract a tablet, the cap 102 is slipped off of the container as shown in Fig. 12 and the tablet positioned in the opening grasped by the fingers and pulled against the tongues 97 and 98 whereby said tongues are spread apart permitting the tablet to be removed from the container.

The modification of the invention shown in Figs. 14-16 differs from the form shown in Figs. 11-13 in that the container 105 is formed with an inlet opening 106 in the same end of the container with the dispensing opening 107. The inlet opening is at the other corner of said end and is sufficiently large to permit the container to be filled with tablets through said opening. The inlet opening 106 is normally closed by a hinged closure member 108 comprising a strip 109 of plastic or other suitable material fastened at one end to the top wall 110 of the container, the other end 111 of the strip spanning and closing the opening 106 and extending over the adjacent corner of the container and being secured to the adjacent end thereof.

In all other respects the form of invention shown in Figs. 14-16 is similar to the form of Figs. 11-13 and similar reference numerals are used to indicate similar parts.

In every form, the dispensing action is the same, as will be readily apparent, and it will be seen that in no circumstances can more than one tablet be accidentally dispensed at a particular time. This eliminates the inconvenience and waste resulting from the loss of tablets from ordinary containers in which said tablets are merchandised ordinarily.

Of course, the sliding housings and containers could be formed with complementary rounded protuberances and recesses for yieldingly holding the housings in closed positions.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A tablet dispenser comprising a container adapted for holding a quantity of tablets to be dispensed, said container having a rectangular-shaped body with a dispensing opening at one corner at one end thereof, the body including walls meeting at said corner to normally restrict the opening, the meeting portions of said walls

constituting as spring tongues spreadable against the spring tension thereof to permit passage of a tablet out of the container, said tongues meeting at right angles, said body having an inlet opening at the other corner of said one end for filling the container with tablets, and a hinged strip of plastic secured to the top wall of the body for closing said inlet opening.

2. A tablet dispenser comprising a container adapted for holding a quantity of tablets to be dispensed, said container having a rectangular-shaped body with a dispensing opening at one end corner thereof, the body including walls meeting at said corner normally to restrict the opening, the meeting portions of said walls constituting spring tongues spreadable against the spring tension thereof to permit passage of a tablet out of the body, 15 said tongues meeting at right angles, a partition extending

along the longitudinal center of the body from one end to a point short of the other end forming a tortuous path within the body along which the tablets move, and a hinged closure member carried by the end wall adjacent the opening for closing said opening, including a flexible strip of plastic secured at one end to said end of the body and a thin sheet metal box-like structure secured to the other end of the strip, said structure having opposed flexible side walls and a top wall closing said

10 opening.
